UNITED STATES PATENT OFFICE.

BYRON E. ELDRED, OF NEW YORK, N. Y., ASSIGNOR TO COMBUSTION UTILITIES COMPANY,
OF NEW YORK, N. Y., A CORPORATION OF NEW YORK.

GAS-PRODUCER CONTROL.

No. 908,454.

Specification of Letters Patent.

Patented Jan. 5, 1909.

Application filed April 15, 1905, Serial No. 255,663. Renewed May 23, 1908. Serial No. 434,542.

To all whom it may concern:

Be it known that I, BYRON E. ELDRED, a citizen of the United States, and a resident of New York city, in the county of New York and State of New York, have invented certain new and useful Improvements in Gas-Producer Control, of which the following is a specification.

This invention relates to apparatus for manufacturing producer gas in which carbon dioxid is used as the endothermic or cooling agent.

The invention relates specifically to means for the regulation and control of the gas current supplied to the producer.

In the operation of a gas producer by means of carbon dioxid a fan blower or exhauster is found a convenient means for propelling the gaseous products of combustion from a stack or furnace into the producer. It occasionally happens that on stoppage of the fan the conduit extending from the fan to the stack is not properly closed, whereupon a back pressure is exerted, due to the draft of the stack, and combustible gas may be drawn over into the stack or furnace and give rise to explosions therein or in the conduits or connecting flues. Such explosions are often destructive to the apparatus and means for their prevention are at the present time of great importance for the reason that products of combustion are coming into extensive use in the operation of gas producers.

The object of my invention is to prevent automatically the drawing over of combustible gas into the stack or furnace, and to prevent the explosions consequent thereupon.

I will now proceed to describe my invention with reference to the accompanying drawings, in which:

Figure 1 shows diagrammatically and partly in elevation, and partly in vertical section, an apparatus embodying my invention, comprising a gas producer, a furnace stack, and means for drawing products of combustion from such stack and conducting the same to the producer, comprising automatic means for preventing back flow of the combustible gas into the stack. Figs. 2 to 7 inclusive, are detail views, Figs. 2 and 3 showing respectively in vertical section and in plan, the form of the automatic valve illustrated in Fig. 1, Figs. 4 and 5 show respectively in vertical section and in plan, an alternative form of said valve, and Figs. 6 and

7 show respectively in vertical section and in plan, a further alternative form of the said valve.

Referring now at first to Fig. 1, numeral 1 therein designates a gas producer having the feed apertures or hoppers 2, and a gas delivery or discharge pipe 3 in its upper part. The producer is shown equipped with the water seal 4 for the removal of the ash in a finely divided and friable condition. In the lower part of the gas producer is placed a blast baffle 5 against which the blast delivered through the twyer pipe 6 is allowed to impinge and be dispersed throughout the gas generating mass of fuel. 7 is a stack having at its base the flue 8 connecting with a source of products of combustion, as for instance a reverberatory furnace, billet furnace or the like, or with a source of products of combustion and calcination, as for instance a lime or cement kiln. The products of combustion are carried through the conduit 10 to the gas producer 1, being impelled in this direction by the fan blower 11 interposed in said conduit. On the inlet side of the fan is placed an air opening 12 which is regulated by means of the adjustable valve or damper 13. A similar valve 14 is placed in the conduit 10. By adjusting these valves to the proper width of opening the proportion of carbon dioxid and oxygen in the blast mixture supplied to the producer may be regulated. The gases in the stack vary from time to time and consequently frequent adjustment of the above mentioned valves is desirable. On the inlet side of the fan there is also placed in the conduit 10 an automatic gate 15 which is open while the fan is in operation and which closes upon stoppage of the fan.

By reference to Fig. 2 which shows a section of this apparatus and to Fig. 3 which shows a plan of the apparatus the details of construction may be more readily seen. In Fig. 2, 16 is a damper hinged in its upper part so that it may be swung upwardly into the recess 18. When the fan is not in operation this damper hangs vertically and its lower part enters the recess 17. 19 is a lever rigidly fixed to the damper 16 and connected to the slotted arm 20 by means of the rod 21. This arm 20 is fastened at 22 as shown in Fig. 3 to the air damper or valve 23. In operation, the fan having been started, a gas current is impelled in the direction indicated by the arrow 24, and this current impels the lever 19 and the damper 16 upwardly into the recess 18, the lever 19 being so constructed that it will hold the damper 16 in its raised position. The lever 19 is so constructed that it will hold the damper 16 in its raised position.

row, the damper 16 is raised by hand or otherwise, thereby lowering the damper 23 and covering the air inlet 24. The suction on the air opening 24 holds valve 23 over said opening and is sufficient to hold the damper 16 in a horizontal position in the recess 18. On stoppage of the fan the suction or pressure on the air opening 24 is relieved and the valve or damper 16 drops back into a vertical position thereby closing the main passage and opening the air inlet. The gas from the producer is therefore prevented from working backward into the stack or furnace and the entrance of the air through the opening 21 prevents any suction from the chimney exerting its influence in the gas producer. It is not ordinarily possible to make the joint around the damper 16 so tight that no gas will be drawn past this damper into the stack 20 on stoppage of the fan. The air opening 24 when the suction operated valve 23 is opened allows of the admission of air and in as much as the gas flow will be along the path of least resistance any leakage through or past the damper 16 will be merely that of the air entering at 24 and not combustible gas from the producer.

Figs. 4 and 5 show another form of apparatus which is of simpler construction but which does not damper or close the pipe to prevent the back flow of gas, but depends simply upon admitting air to relieve the back pressure. In said drawing 25 is a disk closing an opening in the main conduit. This disk is supported by the rod 26 sliding in the bearing 27, which is secured to a support 28. This apparatus is placed on the exhaust side of the fan and the disk 25 is held in place by the blast pressure. On stoppage of the fan 40 the pressure will be so greatly reduced that the disk 25 moves downward allowing air to enter the conduit. The draft from the chimney will thereupon draw air in at this point rather than draw back combustible gas from the gas producer against a greater resistance.

Figs. 6 and 7 show a form of apparatus similar to that illustrated in Figs. 2 and 3. 16 is the damper shown hanging in a vertical position. 17 is the recess in the lower part 50 of the conduit adapted to receive and hold in position the damper as it swings downwardly into place. 18 is a recess 20 a slotted rod attached at 33 to the balanced valve or damper 34. The operation of this apparatus is 55 similar to that shown in Fig. 2.

I have found that when carbon dioxid is used in gas producers, it is desirable to have some means for indicating the temperature of the producer gas as it leaves the producer. 60 Heretofore most gas producers have used steam, and such producers require a high temperature in order that the water gas reaction may take pressure satisfactorily. In the case of the use of carbon dioxid, the de- 65 composition resulting in the production of

combustible gas, takes place at a lower temperature, consequently it is desirable to run a carbon dioxid controlled gas producer on a lower temperature plane than that customarily in the operation of the gas producers 70 employing steam. The gas producer operators, however, accustomed as they are to the operation of steam-using gas producers at a relatively high temperature plane, refuse to run the gas producer operated by carbon 75 dioxid at the lower temperature needful for the economical practice of this method. Accordingly, I place in the delivery pipe 3 of the gas producer a device for indicating the temperature of the departing gas. This apparatus is shown at 35. It may be a thermostat consisting of two metal plates having different co-efficients of expansion. The aforesaid metal plates are riveted and fastened at one end to a support so that by 80 changing the temperature the strap so produced is caused to buckle or bind thereby making electrical contact and operating a galvanometer or ringing an electric bell. As shown in the drawing a thermo-electric 85 couple is placed in the socket 35 and this actuates a galvanometer 37, the needle of which is arranged to close a second circuit, thereby sounding the electric bell shown at 38. A battery 39 is placed in this circuit. The 90 pressure of the gas coming from the producer is subject to variation from time to time, due to the demands of the furnace in which the gas is burned.

To indicate the pressure of the outgoing 100 gas, apparatus of the following description may be used. 41 is an inverted receptacle working in an upright receptacle filled with water or other liquid after the fashion of a spirometer or gasometer. A pipe 43 communicates with the upright receptacle from the delivery pipe of the gas producer 3. A rod attached to the upper receptacle 41 makes contact on the resistance board 44 at certain points, thereby causing the ammeter 105 45 to register according to the strength of the current. This is dependent upon the height of the vessel 41 and this vessel moves upward or downward depending on the pressure of the combustible gas. 110

What I claim is,

1. The combination with a gas producer and means comprising a conduit for supplying products of combustion or equivalent gas thereto, and draft producing means, producing a flow of gas through such conduit, of an automatically opening valve normally closing an opening in such conduit, but opening automatically when said draft producing means ceases to operate. 120

2. The combination with a gas producer and means comprising a conduit for supplying products of combustion or equivalent gas thereto, and draft producing means, producing a flow of gas through such conduit, of a 130

suction-closed valve normally closing an opening on the suction side of said draft producing means.

3. The combination with a gas producer and means comprising a conduit for supplying products of combustion or equivalent gas thereto, and draft producing means, producing a flow of gas through such conduit, of automatic valve mechanism comprising a valve for closing said conduit, said valve normally open, and automatic means causing said valve to close when said draft producing means ceases to operate.

4. The combination with a gas producer and means comprising a conduit for supplying products of combustion or equivalent gas thereto, and draft producing means, producing a flow of gas through such conduit, of automatic valve mechanism comprising a valve for closing said conduit, said valve normally open, another valve normally closing an opening in said conduit on the suction side of said draft producing means, and means connecting said valves.

5. The combination with a gas producer and means comprising a conduit for supplying products of combustion or equivalent gas thereto, and draft-producing means, producing a flow of gas through such conduit, of valve mechanism for preventing back flow of gas through such conduit, comprising the connected valves, one adapted to close such conduit, the other to close an opening in the conduit, said latter valve normally held closed by suction and when so closed holding open the other valve.

6. The combination with a gas producer, a furnace flue and a conduit connecting said flue with the inlet side of the gas producer, of draft producing means and an automatically opening valve normally closing an opening in such conduit but opening automatically when said draft producing means ceases to operate.

7. The combination with a gas producer, a

furnace flue and a conduit connecting said flue with the inlet side of the gas producer, of draft producing means and an automatic valve mechanism comprising a valve for closing said conduit, said valve normally open, 50 and automatic means causing said valve to close when said draft producing means ceases to operate.

8. The combination with a gas producer, a furnace flue and a conduit connecting said flue with the inlet side of the gas producer, of draft producing means and an automatic valve mechanism comprising a valve for closing said conduit, said valve normally open, another valve normally closing an opening in 60 said conduit on the suction side of said draft producing means, and means connecting said valves.

9. The combination with a gas producer, a furnace flue and a conduit connecting said flue with the inlet side of the gas producer, of draft producing means and a valve mechanism for preventing back flow of gas through such conduit, comprising the connected valves, one adapted to close such conduit, 70 the other to close an opening in the conduit, said latter valve normally held closed by suction and when so closed holding open the other valve.

10. The combination with a gas producer, 75 a fuel burning device constituting a source of supply of carbon dioxide and a conduit connecting said source with the draft inlet of the producer, of valve means operable to close the conduit against said source of supply and 80 also simultaneously to open the conduit to the atmosphere between the closure and the producer.

Signed at New York city, in the county of New York, and State of New York, this 12th 85 day of April, A. D. 1905.
